UNITED STATES PATENT OFFICE.

THOMAS F. ROWLAND, OF GREEN POINT, NEW YORK.

IMPROVED APPARATUS FOR LAUNCHING VESSELS.

Specification forming part of Letters Patent No. **38,418**, dated May 5, 1863.

To all whom it may concern:

Be it known that I, THOMAS F. ROWLAND, of Green Point, in the county of Kings and State of New York, have invented a new and Improved Mode of Controlling the Launching of Vessels; and I do hereby declare that the following is a full, clear, and exact description of the same, reference being had to the accompanying drawings, forming part of this specification, in which—

Figure 1 is a side view, partly in section, of a portion of the ways for launching a vessel. Fig. 2 is a transverse vertical section of the same.

Similar letters of reference indicate corresponding parts in the two figures.

To enable others skilled in the art to make and use my invention, I will proceed to describe its construction and operation.

A A are the lower or permanent ways, and B B their supporting-blocks.

C C are the upper or sliding ways, fitted to the permanent ways and combined with the vessel in the usual manner.

D is the catch-shaft, fitted to bearings a a in the permanent ways, just below the surfaces thereof.

b b are the catches, so formed and so arranged upon the shaft that they may be turned back, as shown in red outline in Fig. 1, into recesses provided for their reception in the ways A A in rear of the bearings a a, or be turned upward into the notches or mortises c c, provided for their reception in the ways C C, as shown in black outline in the same figure. The said notches or mortises are fitted with cast-iron lining-pieces d d, and they and the catches are so shaped that the catches entering them, as shown in black in Fig. 1, may serve to prevent the ways C C from sliding

down A A, provided the shaft is properly secured from turning.

E E are levers fitted to squares on the ends of the shaft D, or otherwise so applied thereto as to cause the said shaft to turn with them, and prevent it from turning without them.

Before bringing the whole weight of the vessel upon the ways, as is necessary preparatory to launching, the shaft is turned by means of the levers E E into the position shown in black outline in Fig. 1, and the levers are then secured by suitable means to prevent the shaft from turning until the blocks have been removed from below the keel, and all other obstructions to the movement of the sliding ways have been removed, and the men employed in removing them have all escaped, when, by turning the shaft by means of the levers, or allowing it to be turned by the pressure of the sliding ways against the catches b b to the position shown in red outline, the sliding ways are liberated, and, with the vessel upon them, slide down the permanent ways A A.

It is obvious that the catch-shaft may be attached to the upper or sliding ways, and the catches engage in notches in the lower or stationary ways; but the arrangement first described is in some respects preferable.

What I claim as my invention, and desire to secure by Letters Patent, is—

The arrangement or use, in connection with the ways A C, of the rotating shaft D, extending from one set of ways to the other, and provided with catches b, all operating in the manner herein shown and described.

THOS. F. ROWLAND.
